UNITED STATES PATENT OFFICE.

JOSEPH FRENCH, OF WOONSOCKET, RHODE ISLAND, ASSIGNOR OF ONE-HALF TO THE SEWING MACHINES SUPPLIES COMPANY, OF BOSTON, MASSACHUSETTS, A CORPORATION OF MASSACHUSETTS.

INKING DEVICE FOR STAMPING AND NUMBERING MACHINES.

No. 872,281.

Specification of Letters Patent.

Patented Nov. 26, 1907.

Original application filed July 13, 1906, Serial No. 326,035. Divided and this application filed October 30, 1906. Serial No. 341,322.

To all whom it may concern:

Be it known that I, JOSEPH FRENCH, a citizen of the United States, residing at Woonsocket, in the county of Providence, 5 State of Rhode Island, have invented a certain new and useful Improvement in Inking Devices for Stamping and Numbering Machines, of which the following is a specification, reference being had therein to the accompanying drawings.

The invention relates to inking-pads and holding means therefor.

While not restricted to use in connection with machines of any particular construction, the invention has been designed with a view to application to machines of the general class of which the machine of United States Letters Patent to J. D. Humphrey and myself No. 660,512, dated October 23, 20 1900, constitutes an example.

The invention consists in a detachable inking-pad combined with novel means of holding the same removably in working position in a machine of the general class aforesaid.

The present invention is shown in the accompanying drawings applied in connection with a machine embodying the improvements which are shown, described, and 30 claimed in my application for United States Letters Patent for improvements in stamping and numbering machines, filed July 13, 1906, Serial No. 326,035, of which this case is a division.

In the drawings,—Figure 1 shows the machine of my application aforesaid in side elevation. Fig. 2 is a plan view of an inking-pad holder and pad showing an embodiment of the present invention. Fig. 3 is a 40 bottom view of the parts shown in Fig. 2. Fig. 4 is an edge view of the said parts. Fig. 5 shows the inking pad, detached, in plan. Fig. 6 shows the latch, separately. Fig. 7 shows the ejector, separately.

Having reference to the drawings,—at 1, Fig. 1, is represented the fixed frame or base of the machine, and at 2 is shown the vibrating arm, constituting the type-head carrier. At 22 is a type-head carried by the said arm.

At 2^a is the shaft on which the said arm is fixed, 1^a being one of the bearings with which the said frame or base is formed or provided for the reception of the said shaft, and within

which bearings the shaft rocks as the arm is actuated. As in the Letters Patent and application aforesaid, the actuation of the arm 2 is effectuated by means of a cam (not shown) mounted upon the shaft 4.

At 1^b is one of the bearings with which the frame or base 1 is formed or provided for the support of the shaft 4. The said shaft, it having fixed thereon also the cam (not shown) by means of which the inking devices are actuated, is actuated intermittently at the will of the operator by motion-transmitting and clutch-devices which are or may be substantially the same as in the Letters Patent and application aforesaid. The said motion-transmitting devices comprise the driving-shaft 5 mounted in bearings (one of which is shown at 1^b, Fig. 1,) upon the fixed frame or base, 1, the said driving shaft being provided with the band-pulley 5^a which in practice receives a driving-band or cord, not shown, and also being provided with a spur-pinion 6 fixed thereon and meshing with a spur-gear 7 mounted upon shaft 4 with capacity to turn loosely thereon, but having combined therewith in practice the clutch-devices aforesaid by means of which, when it is desired to actuate the arm 2 for the purpose of printing or stamping, the said spur-gear 7 is clutched for one revolution to the shaft 4 and at the end of such revolution is caused to become automatically unclutched therefrom. By a rotation of the shaft 4 produced in the manner indicated, the vibrating arm or type-head carrier 2 is caused by the actuating cam on said shaft to make a working stroke and then return to its elevated retracted position of rest.

At 13 is the inking-pad support, and at 14, 15, is shown the carrier-arm therefor. The forward portion of the said carrier-arm is connected pivotally to the lower extremities of suspending arms, one of which is shown at 16^a, the said suspending arms being in turn connected pivotally at their upper ends with the type-head carrier arm 2. The rear portion of the carrier-arm 15 is connected pivotally to the upper extremity of a lever, partly indicated at 17, which is actuated by means of a cam (not shown) upon the shaft 4, and co-operating contracting spiral spring 19, one extremity of which spring is connected to the lever 17 and the

other to a fixed pin or stud 19^a rising from the rear portion of the fixed base or frame 1. As shaft 4 rotates, the inking-pad support is advanced by means of the said cam, and by 5 the swinging movement of the supporting arms 16^a its forward end is raised to press the inking-pad against the printing surfaces of the type-head while the latter still retains its elevated retracted position, and then 10 prior to the movement of the type-head toward the work is lowered partly and withdrawn from between the type-head and the work. A portion of one of the type-wheels of the printing-head is indicated at 20. At 15 52^a is a work-supporting cushion or pad carried by a base 52, and at 52^b is a work-gage at the rear of said cushion or pad.

At 31^c is an inking-pad. For the reception of the said inking-pad, the inking-pad support 13 is furnished with a pad-holder 32^a, which is constructed to receive the inking-pad, and is provided with a spring-actuated latch 33, shown separately in Fig. 6, by which the pad ordinarily is locked in place. 20 In addition the said support 13 has provided in connection therewith a combined relief-device and ejector 34, also spring-actuated, shown separately in Fig. 7. The inking-pad is composed of a metallic frame or body, and 25 a cushion made of suitable ink-absorbing substance, and is furnished at the sides thereof with oppositely-projecting lugs 31^b, 31^c, Fig. 5. The holder 32^a is formed with an opening to receive the inking-pad, and occupies a position slightly raised from the plate or bed of the inking-pad support 13, it being provided in the present instance with spacing pieces or studs 32^b, 32^c, etc., that rest upon the said plate or bed and sustain the 30 holder at the proper distance above the surface of the plate or bed.

Within the space between the holder and the plate or bed is fitted the combined relief-device and ejector 34. The latter is U-shaped in plan as shown best in Fig. 7 to receive and partly inclose the rear portion of the inking-pad 31^c as indicated in Fig. 2. It is movable in a direction from front to rear, being guided in its movements by 45 means of the pin or stud 34^a, carried by its rear portion and working in a slot 32^c in the rear portion of the holder, and also by means of the studs, rivets, or screws 32ⁱ, 32^j, at the opposite sides of the holder, the outer edges 50 of its side-arms making contact with the said studs, etc. For the purpose of transmitting to the said relief-device and ejector the elastic force of an actuating spring 36, in such manner as to press the said device forwardly 55 with relation to the holder, a swinging arm 37 is pivoted at 37^a in connection with the holder and has its free end engaged within a notch 34^b which is formed in the rear portion of the relief-device and ejector.

60 In my application aforesaid I have shown

and described two inking-pad holders, one thereof fixed in position upon the inking-pad support, and the other adjustable upon the said support transversely of the printing-head in unison with the type-head 22. For 70 convenience I have shown the adjustable inking-pad holder herein. It is provided with a cross-bar or plate 32^b fitting within a slot that is made through the support 13 and that extends in the direction of the length of 75 the said support. The said cross-bar or plate is movable longitudinally within the said slot to permit of the adjustment of the said holder lengthwise of the support, and serves to guide the adjustable holder in being 80 adjusted, as well as to keep such holder in proper working position. The latch 33 is pivoted to the body of the holder at 33^b, and for the purpose of actuating the latch to cause it to engage with the corresponding 85 lug 31^b of the inking-pad, and retain the latter in place within the holder, it has connected therewith one extremity of the spring 36 which has been mentioned already as having an extremity thereof connected with the 90 arm 37 in engagement with the combined relief-device and ejector. Thus the latch and the relief-device and ejector are connected by means of the said spring, which serves 95 for the actuation of both thereof. The engaging portion of the latch is pushed outward by the pressure against the inclined inner face of the same of one of the lugs 31^b of the inking-pad as the latter is being inserted into place within the holder. As the inking- 100 pad passes rearwardly into proper position within the holder, its opposite lugs engage the forward or free ends of the side-arms of the combined relief-device and ejector, pressing such device rearwardly and straining the spring 36. As soon as the lug which 105 acts against the inclined face of the engaging portion of the latch passes such portion, the latch is caused by the tension of spring 36 to snap into position in front of the said lug, 110 thereby locking the inking-pad in place, the lug in question being confined between the said engaging portion of the latch and the end of the adjacent side-arm of the combined relief-device and ejector. The spring 36 115 acts through the arm 37 with a tendency to hold the combined relief-device and ejector, together with the inking-pad, forward with the said lug in contact with the said engaging portion of the latch. When the movement 120 of arm 15 relative to the type-head carrier carries the inking-pad into contact with the printing characters, the spring gives way so as to permit the inking-pad to yield backward in the holder sufficiently to obviate 125 scraping of the inking-pad upon the surfaces of the printing-characters. In this manner, the relief-function is secured. When latch 33 is pressed back transversely by hand so as to disengage it from the lug 31^b with which it 130

co-acts, the spring 36 acts through arm 37 to move the combined relief-device and ejector forward so as to push the inking-pad out of the holder. The forward movement 5 of the said device is limited by the contact of side-shoulders 32^a, 32^b, which are formed on the edges of the arms of such devices, with the studs 32ⁱ, 32^j.

The extent of the swinging movement of 10 latch 33 is limited by means of one of the studs 32^b, the said latch having formed therein a slot 33^c, the opposite end-walls of which make contact with the said stud. For the purpose of causing the inking-pad 15 holder 32^a to accompany the adjustable type-head 22 as the latter is shifted, a rocker-arm 38 is mounted pivotally upon one side-piece of the said adjustable type-head, the lower portion of such rocker-arm being connected pivotally with the stud 39, Figs. 2 and 20 3, projecting laterally from the body of the holder 32^a. The said lower portion is forked to fit upon the neck of such stud between an arm of the said body and a collar or flange 25 which is formed upon the stud. Consequently, when the adjustable type-head is shifted in one direction or the other, the corresponding inking-pad holder is compelled to accompany the same. The pivotal connection 30 of the respective ends of the rocker-arm 38 with the adjustable type-head and with the adjustable inking-pad holder, permits the swinging movement of the inking-pad support with relation to the type-heads to 35 take place without affecting the connections.

I claim as my invention:—

1. In combination, a type-head, operating means therefor, an inking-pad support having a swinging movement, operating means therefor, an inking-pad removably connected 40 with the said support, a relief-spring operatively connected with the said inking-pad to permit the same to yield as described to obviate scraping, and a latch by which the inking-pad is retained in its working relations 45 against the pressure of the said relief-spring.

2. The combination with the inking-pad support, and an inking-pad, of a spring-actuated combined relief-device and ejector applied to the said support. 50

3. The combination with the inking-pad support, an inking-pad, and a pad-holder having an opening to receive the inking-pad, of a combined relief-device and ejector, and a latch to retain the inking-pad in place with- 55 in the said holder.

4. The combination with the inking-pad support, an inking-pad, and a pad-holder, of a combined relief-device and ejector, a latch to retain the inking-pad in place within the 60 said holder, and a spring connected with said combined relief-device and ejector and with the said latch.

In testimony whereof I affix my signature in presence of two witnesses.

JOSEPH FRENCH.
